Letters Patent, No 265. Dated Feby 12. 1850. Ante-dated Nov 17. 1849.

The schedule referred to in these Letters Patent and making part of the same.

To all whom it may concern:

Be it known, that I, Sam'l D. Vose in the City
& County of Albany, State of New York, have invented or produced a new ornamental design for a
Parlor Book-ing Store and I do hereby declare that the accompanying drawings are a full and accurate
representation of my said design.

Fig 1, being a perspective view. Fig 2, a view of the top, on a larger scale. Fig 3,
a view of the front. Fig 4, a view of the side. The figures 2, 3 & 4, showing the detail of the
ornaments. To save labor in drawing, but one half of the ornaments upon the plates represented
in Fig 3, are delineated: the remaining portion being similar to and symmetrical
with those represented. The figures are not easily described in words but are fully represented
in the drawings. The borders indicated at a b & c d Fig 2 are continued entirely around their
respective panels.
